UNITED STATES PATENT OFFICE.

FREDERICK WILLIAM BOULTON, OF BOOTLE, NEAR LIVERPOOL, ENGLAND.

LIFE-BOAT.

1,190,371.

Specification of Letters Patent. Patented July 11, 1916.

Application filed August 26, 1915. Serial No. 47,505.

To all whom it may concern:

Be it known that I, FREDERICK WILLIAM BOULTON, a subject of the King of Great Britain, residing at Bootle, near Liverpool, England, have invented certain new and useful Improvements in Life-Boats, of which the following is a specification.

The principal objects of the present invention are to provide a life-boat of the flat bottom type designed with a view to increase the strength and seating capacity thereof; to provide for the general comfort, safety and convenience of passengers and crew; and to economize space in the stowage of a life-boat upon a vessel deck.

Other and further objects of the present invention reside in the providing of general details of construction and arrangement and combination of parts as will hereinafter more fully appear.

The invention consists of the improvements hereinafter described and finally claimed.

The nature, characteristic features and scope of the invention will be more fully understood from the following description taken in connection with the accompanying drawings forming part hereof and in which:

Figure 1, is a view in plan of the life-boat embodying the invention, the one side being broken away to disclose a detail of construction. Fig. 2, is a view in longitudinal section thereof. Fig. 3, is a view in transverse section taken upon the line 3—3 of Fig. 2, and Fig. 4, is a similar view taken upon the line 4—4 of Fig. 2.

Generally considered, the life-boat 10, is of the flat bottom type, and its bottom tapers slightly upwardly, fore and aft upon a curved line, as at 11. Extended the full length of the boat bottom including the tapered portions thereof, are keelsons 12, of which there are two. The outer frame work or shell of the life-boat may be of usual construction. In order to add strength and rigidity to the shell sides, transversely disposed members 15, are present, of which there are six. These members extend from gunwale to gunwale, as shown. These members comprise planking, disposed edgewise, and as shown in Fig. 3, are somewhat U-

shaped in configuration, gradually tapering off toward the respective gunwales. Within the shell thus constructed is an inner frame work embracing longitudinal bulk-heads 16, and transverse bulk-heads 17, which bulk-heads are spaced apart from the outer shell and extend upwardly but about halfway of the height of the life-boat, and provide a passenger receiving compartment. 55 The space surrounding this compartment is preferably utilized for containing buoyancy tanks 18, upon the starboard and port sides of the life-boat and for fresh water tanks 19, fore and aft. Extended across or spanning 60 the space formed between said outer shell and said bulk-heads is planking 20, forming in effect a deck, midway of the height of the boat, as shown. Thus constructed the passenger compartment of the life-boat is protected entirely therearound by a series of 65 compartments formed, to wit: fore and aft by bulk-heads 17, the bulk-heads 16, outer shell and the intersecting uprights of members 15. Thus staving in of the shell at any 70 individual compartment leaves the remaining compartments intact, with a buoyancy tank in each, it being understood of course that all parts of the boat are made water-tight according to the boat builders' art. 75 Within the passenger compartment and built upon the thwarts of members 15, are seats 21, beneath which may be stored bread tanks 22. Upon the starboard and port decks of the boat and built around the 80 tapered ends of the uprights of members 15, in fixed position, are other seats 23. In practice, these seats which are in a plane above those occupied by passengers are occupied by the crew or others manning the 85 life-boat, and are separate and apart from those occupied by the passengers. To accommodate additional passengers fore and aft, seats 24, are provided upon the deck, as shown. Beneath these may be stored oil 90 tanks 25, fitted for distributing oil on the water, the object of which is to prevent the sea from breaking on board. To provide for the convenience and comfort of the passengers and crew, private retiring compartments 26, equipped with proper toilet facilities are present, preferably upon the for- 95 100

ward deck, as shown. These compartments are formed by partitions 27, joined to the outer shell, in combination with movable hoods 28. The hoods are formed from suitable material of a pliable nature and are cooperatively mounted with respect to frames 29, hinged to partitions 27, so that the hoods may be raised or lowered when desired. Thus when the life-boat is stowed upon the 10 deck of a vessel, these hoods lie substantially flush with the top edge of the life-boat. It is to be noted in this respect that the frame tops are angular as at 30, so as to nest with the boat gunwales when in collapsed position, see Fig. 1. Obviously, masts, oarlocks, 15 oars, paddles and other accessories may be provided as usual to fully equip the boat, and hooks 31, at each end of the boat are present, for use in lowering the same from 20 davits.

A life-boat thus constructed and equipped possesses the advantage of maximum passenger and crew accommodating facilities according reasonable comfort to both combined with minimum space occupying dimensions for stowage edgewise upon a vessel 25 deck.

What I claim is:

1. A flat bottom life-boat embracing spaced inner and outer frames to provide a 30 central passenger receiving compartment and surrounding buoyancy chambers, the outer frame being extended in fixed position for an appreciable distance above the top of the inner frame, decks covering the spaces 35 between adjacent frames and partitions, each embracing a horizontal and two vertical members disposed athwart the life-boat and each extended in a continuous manner from gunwale to gunwale to intersect both 40 the central compartment and the starboard and port buoyancy chambers.

2. A flat bottom life-boat embracing spaced inner and outer frames to provide a 45 central passenger receiving compartment and surrounding buoyancy chambers, the outer frame being extended in fixed position for an appreciable distance above the top of the inner frame, decks covering the spaces 50 between adjacent frames, partitions, each embracing a horizontal and two vertical members disposed athwart the life-boat and each extended in a continuous manner from gunwale to gunwale to intersect both the 55 central and the starboard and port buoyancy chambers to provide individual compartments, and seats within the passenger compartment and upon deck arranged athwart the boat, said seats being supported in fixed 60 position by said partition member.

3. A flat bottom life-boat embracing spaced inner and outer frames to provide a central passenger receiving compartment and surrounding buoyancy chambers, the

outer frame being extended in fixed position 65 for an appreciable distance above the top of the inner frame, decks covering the spaces between adjacent frames, partitions each embracing a horizontal and two vertical members disposed athwart the life-boat and each extended in a continuous manner from gunwale to gunwale to intersect both the central and the starboard and port buoyancy chambers, passenger seats arranged athwart the boat within the central compartment 70 and supported by the horizontal members, 75 seats for the crew located upon the decks and supported by the vertical members, said seats being also disposed athwart the body, and retiring compartments for at least one 80 end of the life-boat located upon said deck.

4. A flat bottom life-boat embracing spaced inner and outer frames to provide a central passenger receiving compartment and surrounding buoyancy chambers, the 85 outer frame being extended in fixed position for an appreciable distance above the top of the inner frame, decks covering the spaces between adjacent frames, partitions each embracing a horizontal and two vertical 90 members disposed athwart the life-boat and extended from gunwale to gunwale in a continuous manner to intersect the central compartment and the buoyancy chambers, retiring compartments for at least one end of the 95 life-boat located upon said decks, and collapsible screens operative for rendering private 100 said retiring compartments.

5. A life-boat construction embracing spaced inner and outer frames to provide a 100 central passenger compartment and surrounding buoyancy chambers, decks covering the spaces between adjacent frames, substantially U-shaped members disposed 105 athwart the life-boat from gunwale to gunwale and intersecting the starboard and port buoyancy chambers to provide a series of individual compartments, seats within the passenger compartment and upon the deck and supported by said U-shaped members, 110 retiring compartments for at least one end of the boat located upon deck and collapsible screens operative for rendering private 115 said retiring compartments.

6. A life-boat construction embracing a 115 central passenger compartment, starboard and port decks in a plane above said compartment for accommodating a boat manning crew, retiring compartments for at least one end of the boat located upon the 120 boat deck, and a collapsible frame equipped with a hood operatively mounted with respect to each retiring compartment for rendering the same private, each frame being shaped to correspond to the contour of the 125 boat gunwale and to nest therewith when in collapsed position.

7. A life-boat structure embracing a cen-

tral passenger compartment, starboard and port decks in a plane above said compartment for accommodating a boat manning crew, retiring compartments for at least one end of the boat located upon said decks and a hinged frame for each of said retiring compartments provided with a hood, said frame being shaped to correspond to the

contour of the boat gunwale and nest therewith when in collapsed position.

In testimony whereof, I have hereunto signed my name.

FREDERICK WILLIAM BOULTON.
